FIG. 1

FIG. 4

FIG. 3

FIG. 2

Inventor
T. E. Taylor
By Red B. Billman

UNITED STATES PATENT OFFICE.

THOMAS E. TAYLOR, OF MANSFIELD, OHIO, ASSIGNOR TO THE ECLIPSE STOVE COMPANY, OF MANSFIELD, OHIO, A CORPORATION OF OHIO.

PORTABLE STOVE.

1,342,072.

Specification of Letters Patent.

Patented June 1, 1920.

Application filed June 9, 1919. Serial No. 302,838.

To all whom it may concern:

Be it known that I, THOMAS E. TAYLOR, a citizen of the United States, residing at Mansfield, in the county of Richland and State of Ohio, have invented certain new and useful Improvements in Portable Stoves, of which the following is a specification.

My invention relates to improvements in portable stoves, and more particularly to that class or type known as "knock-down" stoves which are adapted to be readily disassembled and nested, so to occupy but little space in transportation or storage.

15 The present embodiment of the invention is particularly designed and adapted for use as an "orchard heater" for use in protecting orchards, gardens and other places from frost, which would otherwise injure the fruit or other vegetation.

20 The primary object of the invention is to provide a generally improved portable stove of the class indicated which will be exceedingly simple in construction, cheap of manufacture and efficient in use.

25 A further object is the provision of an improved knock-down heater or stove body having improved joints and means for assembling and disassembling the parts.

30 A still further object is the provision of an improved heater or stove body provided with removable legs and grate, the grate adapted to be removably inserted in the stove body after the legs are inserted or set 35 up and the grate acting as a key or locking member for securing the legs in assembled or set up position.

35 A still further object is the provision of an improved knock-down stove or heater body provided with improved body and grate supporting legs, the removable grate acting when in position to lock or secure the parts of the stove body, as well as the legs, in assembled position for use and acting as 45 the medium for releasing said parts for disassembling preparatory to nesting for transportation or storage.

With the above mentioned and other ends in view, the invention consists in the novel 50 construction, arrangement and combination of parts, hereinafter described, illustrated in one of its embodiments in the accompanying drawings, and particularly pointed out in the appended claims.

55 Referring to the drawings, forming a

part of this specification, Figure 1, is a side elevation of the improved stove in assembled or set up position.

Fig. 2, a horizontal cross sectional view taken on line 2—2, of Fig. 1.

Fig. 3, an enlarged cross sectional view of the detachable joint for the stove, made up of interlocking hooks.

Fig. 4, a fragmentary sectional view of the adjacent assembled parts of the stove body and detachable legs and removable grate, and illustrating the manner in which the latter is supported upon the legs and acts to secure the legs and the base portion of the stove body in assembled position.

Similar numerals of reference designate like parts throughout all the figures of the drawings.

The improved portable stove comprises a suitable stove or heater body 1, said heater body 1, in the present instance, comprising an open ended cylindrical body, and as a means of forming a "knock-down" stove body the latter is preferably formed in two sections of substantially semi-cylindrical shape, as shown in Fig. 2, of the drawings, said sections having their marginal edges bent to form detachable interlocking hooks 1^a, forming a seam or joint, as shown.

If necessary, or desirable, the upper portions of the interlocking hooks 1^a, may be provided with an opening 1^b, adapted to removably receive and contain a locking element 1^c, such as a cotter pin, as shown in Fig. 3, of the drawings.

It will be apparent that when the two-part cylindrical body is detached the semi-cylindrical shaped parts may be readily nested together.

As a means of properly supporting the stove body in its set up position for use, the lower ends of the cylindrical stove body are provided with a plurality or series of circumferentially extending leg receiving openings or slots 1^d, adapted to receive and contain a plurality of stove body and grate supporting legs 2.

As a means of removably inserting and securing the legs 2, in the openings 1^d, of the stove or heater body 1, as well as securely bracing the legs when in assembled position, each leg comprises a main body portion 2, terminating in an off-set grate supporting shoulder 2^a, the latter terminating in a second longitudinally extending portion 2^b,

adapted to rest on the inner side of the cylindrical stove body, said second member 2^b, terminating in a second off-set shoulder 2^c, adapted to extend through the opening 1^d, 5 and forming a stove supporting shoulder when set up. As a means of further securing the legs 2, the shoulder 2^c, terminates in an off-set tongue portion 2^d, adapted to extend on the outer side of the stove body, as shown, 10 and to prevent inward movement of the legs when set up and to interlock therewith, as shown most clearly in Fig. 4, of the drawings. Each leg terminates in a horizontally extending base member 2^e.

15 As a means of securing and locking the parts of the knock-down stove body and the detachable legs in position when assembled or set up, a removable grate 3, is inserted from the top of the cylindrical stove or 20 heater body, the marginal edges of the grate 3, being adapted to rest upon the grate supporting shoulders 2^a, of the legs and prevent the inward movement of the legs and likewise the base portions of the two-part heater 25 body with respect to the joint formed by the interlocking hooks 1^a. It will thus be seen that the grate member 3, acts as a key or lock for holding the removable legs and the base portion of the stove body in assembled position, and that when it is desired to disassemble the parts the grate 3, is first removed whereupon the legs 2, may be moved inwardly to a substantially horizontal position and then withdrawing the 30 tongue portions 2^d, through the openings 1^d, after which the base portions of the cylindrical parts may be moved inwardly to disconnect the hooks 1^a, and if the upper portions of the hooks 1^a, have been secured by a 35 securing elements, such as the cotter pin 1^e, the latter may be removed and the parts of the stove may then be conveniently disassembled for storage or transportation.

40 As a convenient means of carrying or lifting the portable stove with its fuel contents about from one place to another when assembled or set up, the sides of the heater 45

body 1, may be provided with openings 1^f, adapted to receive and contain the bearing ends of a suitable carrying bail 4, and the 50 improved portable stove is preferably provided with a lid 5, having a handle 6, said lid being useful in controlling the draft through the grate portion of the stove.

The base portion of the heater body 1, is 55 provided with draft holes 1^g, just above the grate 3, and may also be provided with poker holes 1^g.

From the foregoing description, taken in connection with the accompanying drawings, the operation and advantages of my invention will be readily understood.

Having thus described one of the embodiments of my invention, what I claim and desire to secure by Letters Patent, is,—

65

1. An orchard heater, comprising a heater body provided with leg receiving openings, leg members removably mounted in the latter and provided with grate supporting shoulders, and a grate removably mounted 70 on the latter and holding said leg members in assembled position.

2. An orchard heater, comprising a two-part open ended cylindrical heater body, 75 grate supporting legs having off-set body and grate supporting shoulders arranged within the lower end of said heater body, and a grate mounted on said grate supporting shoulders of said legs within said cylindrical body and securing said legs and two-part body in assembled position.

3. In a portable stove, an open bottom stove body provided with openings about its lower marginal edges, legs provided with off-set stove body and grate supporting shoulders, said body supporting shoulders extending through said openings and said 85 grate supporting shoulders resting within said lower marginal edges of said stove body, and a removable grate mounted on 90 said grate supporting shoulders.

In testimony whereof I have affixed my signature.

THOMAS E. TAYLOR.
